FURNITURE CASTER

John A. Skupas and Irving Stollman, Evansville, Ind.,
assignors to Faultless Caster Corporation, Evansville,
Ind., a corporation of Indiana

Filed July 17, 1961, Ser. No. 65,950

Term of patent 14 years

(CL. D10—6)

Fig. 1.

Fig. 2.

Fig. 3.

Fig. 4.

Fig. 5.

FIG. 1 is a side view of a furniture caster embodying our new design.

FIG. 2 is a rear view thereof.

FIG. 3 is a front view thereof.

FIG. 4 is a reduced perspective view thereof with the pendant arm omitted for convenience of illustration.

FIG. 5 is a sectional view taken through the diameter of one wheel of the caster.

The dominant features of the design reside in the portion shown in full lines. The wheel members are shaded to show contrast.

We claim:

The ornamental design for a furniture caster as shown and described.
